UNITED STATES PATENT OFFICE.

SIMEON C. KEITH, JR., OF NEWTON, MASSACHUSETTS.

BUBBLING DRINKING-FOUNTAIN.

1,068,142.

Specification of Letters Patent. Patented July 22, 1913.

Application filed November 1, 1910. Serial No. 590,122.

To all whom it may concern:

Be it known that I, SIMEON C. KEITH, Jr., of Newton, in the county of Middlesex and State of Massachusetts, have invented certain new and useful Improvements in Bubbling Drinking-Fountains, of which the following is a specification.

This invention has relation to bubbling drinking fountains and has for its object to provide certain improvements in fountains such as those set forth in my Letters Patent No. 973,790, dated October 25, 1910, and No. 1,019,162, dated March 5, 1912.

When a fountain is provided with means for automatically controlling the flow of water to secure an unvarying height of the bubble irrespective of variations in the pressure of the water being delivered to the fountain, it is desirable that the initial height of the bubble should be capable of regulation according to the requirements of the particular place, to the maximum pressure of water in the service pipes, or to the varying ideas of school or other public officials. This regulation or adjustment may be secured by varying the tension of the spring which bears against the piston of the regulating valve, and the present invention has for its object to provide a convenient and accessible means for effecting the variation of the tension of said spring. Again, one of the objectionable features of a bubbling fountain is that, when the water is first admitted to the fountain from the service pipe by opening a valve or cock, the water is apt to spurt through the outlet port in a fine jet or spray some little distance above the fountain. Another object of the present invention therefore is to prevent the possibility of such spouting or violent discharge of the bubble when the water is first admitted to the fountain and before the casing is partially filled. I have provided a construction in which this is prevented by directing the admission of water to the nozzle which directs it to the outlet port in such way that the water will flow smoothly and evenly from the moment of its first admission to the casing.

As illustrated, the fountain consists of a casing provided with a combined cap and nozzle through which the water is emitted vertically in the form of a low jet or bubble. Within the casing is a piston connected to the regulating valve which controls the port

through which the water is admitted to the casing and under side of the piston; and between the cap and the piston is the spring which opposes the force of the water exerted upon the piston. This is substantially 60 the construction of the fountains as illustrated and described in my said applications.

In carrying out my invention, I secure the variation in the tension of the spring (thereby effecting a change in the height of 65 the bubble) by providing the combined cap and nozzle, and the casing with complementary threaded portions of such length that merely by rotating the cover in one direction or the other and thereby adjusting said cap 70 longitudinally of the casing, the pressure of the spring upon the piston may be increased or diminished, said portions having no contacting shoulders or stops to limit any desired adjustment of said cap. In order, 75 however, that after the cap has been once adjusted to the position to secure a bubble of the desired height, it cannot be tampered with by unauthorized persons, I provide a lock nut, threaded on the casing, which may 80 be set with any such force against the end of the cap that it and the cap cannot be rotated without the use of a proper tool. The cap and the locking nut have substantially cylindrical side walls, and in appearance 85 one forms a continuation of the other, in consequence of which an ornamental effect is secured. In addition thereto, in the illustrated embodiment of the invention, the threads of the nut are interrupted to provide 90 ports between it and the casing to register with the similar ports in the cap through which the water is emitted when the nozzle is mischievously throttled in an attempt to squirt or deflect the water away from its 95 regular course.

The piston is apertured for the passage of water therethrough and is provided with a nozzle located in alinement with the discharge port of the casing. In the present 100 form of the invention, the port through the piston is provided for by inserting through the piston a tube, the lower end of which is closed except for small lateral opposed inlet ports through which the water is admitted 105 to the tube. By arranging these ports transversely to the path in which the water must flow through the tube and by arranging them diametrically opposite each other, the fine streams of water entering the tube are 110

caused to oppose each other, and the water fills the bore of the tube and is discharged without spouting or spraying when it is first admitted thereto.

5 Referring to the drawings, — Figure 1 represents a side elevation of a drinking fountain embodying the invention. Fig. 2 represents a vertical section therethrough on the line 2—2 of Fig. 1. Fig. 3 represents a 10 plan view of the fountain with the cap removed and shows the spring in section. Fig. 4 represents a plan view of the nut. Fig. 5 represents a vertical section on a different plane from that in Fig. 2 to illustrate ports for the passage of water between the casing and the cap and nut. Figs. 15 6 and 7 represent vertical sections through the cap and the nut respectively. Fig. 8 illustrates the exterior of the casing with 20 the parts removed.

The casing is illustrated at 10 and has a substantially cylindrical side wall, and is provided in its lower end with a port 11 which affords communication between the 25 interior of the casing and a chamber in an annular, exteriorly polygonal and interiorly threaded flange 12 by which the fountain is attached to a service pipe 13. Within the casing is located the piston 14 dividing the casing into two chambers. The piston 30 is centrally apertured to receive a tube or sleeve 15, closed at its lower end except for the ports 16, and formed at said lower end with a regulating valve 17 by which the passage of water through the port 11 is controlled. The casing is formed with lugs or 35 projections 18 which form stops for engaging the shoulder on the tube 15 and thus limiting the downward or opening movement of the valve 17. This construction of the piston and valve is advantageous for 40 many reasons, such as its low cost of manufacture, convenience in assembling, etc. The tube 15 constitutes an ejector or nozzle 45 as pointed out in my application Serial No. 551,187, and emits water to the upper chamber, whereby it is discharged or ejected through the main nozzle.

As hereinbefore pointed out, the lateral 50 ports 16 are relatively small and are diametrically arranged so that a stream of water entering one port is met by a stream entering the opposite port. These streams, so meeting and entering at a right angle to the 55 subsequent flow of the water, are prevented from being discharged upwardly so as to spurt, or be discharged upwardly in a fine stream or spray. I regard this as a desirable feature for it eliminates some of the 60 difficulties which I have met with in the manufacture of bubbling fountains.

19 indicates a combined cap and nozzle by which a bubble is emitted vertically from the casing. It is provided with a 65 depending annular flange 20, the bore of which

flares downwardly as illustrated, the diameter of its lower end being greater than the diameter of the tube. Between the cap and the piston is inserted a relatively powerful helical spring 21, the tension or yielding 70 pressure of which against the piston tends to hold the valve 17 away from the port or seat 11. By increasing the tension of the spring, it is apparent that the height of the bubble may be increased, whereas by decreasing its tension, the height of the bubble may be correspondingly lowered. The cylindrical wall of the casing is exteriorly threaded throughout a greater portion of its 75 length as indicated at 22, and the interior of the complementary side wall of the cap is correspondingly threaded as indicated at 23, and consequently the cap may be adjusted 80 without restraint so as to increase or diminish the tension of the spring as may be desired. 85

To lock the cap, I employ a jam nut 24 having interior threads 25 to engage the exterior threads of the casing. The side wall of the cap, and the jam nut are cylindrical 90 and of the same exterior diameter, so that, as illustrated in Fig. 1, one forms to all intents and purposes a continuation of the other, and they inclose the casing to a considerable extent. Both the cap and the jam 95 nut are provided with sockets 26 to receive a spanner or other suitable tool by which they may be rotated. After the cap has been adjusted to proper position to secure the desired height of the bubble, the lock or jam 100 nut is rotated so as to bind it against rotation and adjustment. The lock nut has an unthreaded extension or skirt to cover the threads on the casing and prevent the settling of dust thereon and to add to the 105 finished appearance of the fountain. The cap is provided with ports 27 through which the water is emitted when the port 28 in the cap is closed, such ports being formed by interrupting the threads 23. Similar ports 110 29 are formed between the lock nut and the casing by interrupting the threads 25, and the threads are so cut upon the cap and nut that, when the nut is in its locking position, the ports 29 will register with the ports 115 27. I would not consider it a departure from my invention, however, if the ports were formed by interrupting the threads or grooving the exterior of the casing instead of forming them upon the cap and nut. 120

Having thus explained the nature of my said invention, and described a way of constructing and using the same, although without attempting to set forth all of the forms in which it may be made or all of the modes 125 of its use, what I claim is:

1. In a bubbling drinking fountain, a casing having an inlet port, a piston in said casing having means for permitting the passage of water past it, a regulating valve 130

movable with said piston for controlling the passage of water through said port into said casing, a cap having an outlet for the emission of a substantially vertical bubble, 5 and a spring between said piston and said cap, said casing having an elongated exteriorly threaded portion and said cap having a complementally interiorly threaded portion, whereby the height of the bubble may 10 be varied by adjusting said cap longitudinally of said casing and thereby increasing or diminishing the pressure of the spring upon the piston.

2. In a bubbling drinking fountain, a casing having an inlet port, a piston in said casing, a regulating valve movable with said piston for controlling the passage of water through said port into said casing, a cap having an outlet for the emission of a 15 substantially vertical bubble, a spring between said piston and said cap, said casing having an elongated exteriorly threaded portion and said cap having a complementally interiorly threaded portion, 20 whereby the height of the bubble may be varied by adjusting said cap longitudinally of said casing and thereby increasing or diminishing the pressure of the spring upon the piston, and a lock nut on 25 the threaded portion of said casing to bind the cap against rotation, said cap and nut having similar external cylindrical surfaces,

and said nut having an unthreaded skirt to cover the exposed threads on the casing.

3. In a bubbling drinking fountain, a 35 threaded casing, a cap having threads in engagement with threads of the casing and adjustable longitudinally thereof, said cap having an outlet port for the emission of a jet or bubble, a piston in said casing, a 40 spring between said piston and said cap, the tension of which is varied by the adjustment of the cap, said cap having supplemental outlet ports, for the emission of water when the outlet port is closed, formed 45 by gaps in the threads.

4. In a bubbling drinking fountain, a casing, a cap in threaded engagement with the casing and adjustable longitudinally thereof, said cap having an outlet port for 50 the emission of a jet or bubble, a piston in said casing, a spring between said piston and said cap, the tension of which is varied by the adjustment of the cap, a jam nut on the casing to lock the cap in place, there being 55 supplemental ports between the casing and said cap and nut for the emission of water when the main outlet port is closed.

In testimony whereof I have affixed my signature, in presence of two witnesses.
